UNITED STATES PATENT OFFICE.

ROBERT E. CHAPMAN, OF COLORADO CITY, COLORADO.

TRIPLE VALVE.

No. 809,491.

Specification of Letters Patent.

Patented Jan. 9, 1906.

Application filed September 20, 1904. Serial No. 225,203.

To all whom it may concern:

Be it known that I, ROBERT E. CHAPMAN, a citizen of the United States, residing at Colorado City, in the county of El Paso, in 5 the State of Colorado, have invented certain new and useful Improvements in Triple Valves, of which the following is a specification.

My invention relates to so-called "triple valves" forming a part of the air-brake system of railway-cars in the operations of the brakes by compressed air; and speaking in general terms the object of my invention is to improve the working and efficiency of 15 such valves.

My invention is not only capable of being embodied in new triple valves, but may at small expense be applied or attached to those triple valves now in general use.

20 My invention relates more particularly to the means for feeding or charging the auxiliary reservoir from the train-pipe, which according to my invention is done by a direct check-valved connection between the reservoir

25 and the usual drain-cup of the triple valve, with the result that the feeding air passes directly to the reservoir and not through the valve proper, so that dust, dirt, and scale accompanying or in suspension in 30 the air finds its way into the reservoir where it does no special harm. The comparatively frequent and expensive cleaning and overhauling of the working parts of triple valves is thereby avoided.

35 Again, my invention provides for the rapid charging and recharging of the auxiliary reservoir, thus enabling the engineer to have his train under full control at all times no matter how long or steep the grade may be, 40 and thereby preventing runaway trains.

Other features of advantage and utility in my invention will be apparent or will be explained after the following description of the construction and mode of operation.

45 In the drawing the single figure represents a central vertical section of a standard Westinghouse triple valve to which I have shown my invention applied.

The Westinghouse triple valve herein 50 shown is of the well-known standard construction with the exception that the feed-groove in the bushing 1 of the piston 2 is dispensed with. In applying my invention to old valves in service this feed-groove or by- 55 pass around the piston is closed or plugged up in suitable manner; but in new valves the

bushing is left entire—that is, without the usual cut therein to form the groove.

As is well known, in the standard Westinghouse triple valve the auxiliary - reservoir 60 feed is past the piston, through the slide-valve chamber, and past the slide-valve into the auxiliary reservoir 3, also here indicated by the letters A R. The parts here shown are those of a freight-car equipment, in 65 which case the brake-cylinder connection from the triple valve is had through a pipe 4, passing longitudinally of and through the auxiliary reservoir to the brake-cylinder, (not shown,) which is connected to the outer end 70 of the reservoir. In the present instance said feed past the piston 2 is entirely discontinued, and the feed is had directly from the train-line to the reservoir by means of a connection from the drain-cup 5 of the triple 75 valve, which cup is sometimes designated as the "check-valve" case and which is in direct and immediate communication with the train - line. This feeding connection comprises in the present instance a right-angled 80 pipe 6 at one end screwing into the triple-valve casing and having its other end also screw-threaded in order that it may be connected to another pipe 7, whose upper end screws into the auxiliary reservoir and com- 85 municates therewith. As shown, the connection between the pipes is made by a union-nut 8, which also serves to clamp between the ends of such pipe a guide 9 for the stem 10 of a check-valve 11. This check-valve 90 seats by gravity upon a seat 12, formed in the pipe 6, with the result that under no conditions can the air-pressure flow back to the train-line. However, free passage of the air-pressure is permitted in the opposite direc- 95 tion—that is, from the train-line to the auxiliary reservoir.

The check-valve is of the proper weight, so that the piston will be forced to normal or release position before the check-valve opens 100 for feeding to the auxiliary reservoir. Assuming that the check-valve has a train-pipe exposure of one-fourth of an inch and weighs two ounces, the resistance would be two pounds per square inch, so that with a pis- 105 ton area of nine inches there would be eighteen pounds resisting power on the train-line side of the piston, thus guaranteeing the restoration of the piston prior to the feeding operation.

110 The operation of my device will be understood from the foregoing description, and it

need only be stated that in the feeding operation the check-valve is lifted, thereby opening the direct communication between the train-line and the auxiliary reservoir, and 5 that in the operation of the brakes the check-valve is seated and held thereto by its gravity assisted by the reservoir-pressure.

Several of the advantages of my invention have already been stated, and in addition I 10 will refer to some others. In case the triple-valve piston of the ordinary Westinghouse valve should stick after a train-line reduction the communication between the reservoir and the train pipe or line remains open, 15 thereby permitting such pressure to flow to the train-line and to atmosphere. In a triple valve equipped with my improvements this cannot occur, as the pressure is absolutely cut off from the train-line after once 20 entering the auxiliary reservoir. Again, in the terminal testing of triple valves the clogged condition of the charging-groove around the piston does not manifest itself, because the reservoir is already charged when 25 the service test is made. After such first test is made the auxiliary reservoir is not fully charged or the charging takes a considerable time, both of which conditions are 30 objectionable in practice. Such objections are avoided in triple valves equipped with my invention, inasmuch as the charging-passage cannot clog. Moreover, it often occurs in actual practice that after a service application of the brake the graduating-valve is 35 prevented by dirt from properly seating, with the result that the reservoir-pressure continues to reduce into the brake-cylinder until the train-line pressure is sufficient to

force the slide-valve from lap to release position, so that the braking power of the particular triple valve is lost. It is obvious that this cannot occur in a valve provided with my invention. 40

I claim—

1. The combination with an auxiliary reservoir of an air-brake system, of a triple valve having a pipe connection connected at its end with the triple valve and reservoir and forming connection therebetween, a valve-stem guide separate from and arranged in said pipe connection, and a check-valve arranged in such connection and having a stem coöperating with such guide; substantially as described. 45

2. The combination, with a triple valve 50 and the auxiliary reservoir 3, of a connection between the triple valve and reservoir comprising the pipes 6 and 7 joined by the union-nut 8 and communicating directly between the triple valve and reservoir, a check-valve 60 guide arranged in one of the pipes and clamped therein by the union-nut 8, and a check-valve 11 within the pipe 6; substantially as described. 55

3. The combination, with an auxiliary reservoir, and with a triple valve having a drain-cup 5, of two pipes 6, 7 communicating between such cup and the reservoir, the separate guide 9 in the pipe 6, and a check-valve 11 in such communication and guided by 70 said guide; substantially as described. 65

ROBT. E. CHAPMAN.
